UNITED STATES PATENT OFFICE.

RUDOLPH T. G. LIESINGER, OF BUFFALO, NEW YORK.

SANITARY RENDERING AND DRYING APPARATUS.

1,031,010.

Specification of Letters Patent.

Patented July 2, 1912.

Application filed November 3, 1911. Serial No. 658,443.

To all whom it may concern:

Be it known that I, RUDOLPH T. G. LIESINGER, a citizen of the United States, residing at Buffalo, in the county of Erie and 5 State of New York, have invented a new and useful Sanitary Rendering and Drying Apparatus, of which the following is a specification.

The present invention relates to improvements in sanitary rendering and drying apparatus, the primary object of the invention being the provision of an improved agitator with a special design of arms disposed concentrically within the bottom of the retort 15 and adapted to be rotated to agitate or break up the mass of material and the fat cells, the same also agitating the liquid or wet material before the oleaginous matter has been rendered and drawn from the retort, this agitating causing the oleaginous matter to float to the top where it may be drawn off or rendered.

With the foregoing and other objects in view which will appear as the description 25 proceeds, the invention resides in the combination and arrangement of parts and in the details of construction hereinafter described and claimed, it being understood that changes in the precise embodiment of 30 invention herein disclosed can be made within the scope of what is claimed without departing from the spirit of the invention.

In the drawings—Figure 1 is a front elevation of the complete apparatus, the lower 35 portion of the steam jacket and retort and the upper portion of the retort being broken away and shown in section. Fig. 2 is a section taken on line 2—2 of Fig. 1.

Referring to the drawings, the numeral 1 40 designates the main shell of the apparatus which is composed of a single shell of steel, the lower end of which is surrounded by a steel steam jacket 2, the upper end of the shell 1 being closed by a single disk or head 45 3, while the lower end or bottom is a double steel head 4 composed of two disks as shown in Fig. 1. Formed in the upper head of the shell 1 is the upstanding ring or flange 5 provided with the removable cap or closure 50 5', whereby the retort or shell 1 may be loaded. Connected to the frame 6 in the lower portion of the shell 1 and disposed to be operable exteriorly thereof, is a closure or door 6', to permit the unloading of the dried 55 material from the retort or shell 1.

Connected to the shell 1 in vertical aline-

ment, and arranged at desired distances from the bottom thereof to a point above the steam jacket 2, are three draw-off valves 7, while connected to and in communication with the lower end of the shell 1, is a steam trap 8 for taking care of the condensation in the lower jacket formed by the double bottom and in the steam jacket 2 of the apparatus. 60

Leading from the top of the retort or shell 1, is a pipe 9 provided with a safety valve 9' all of usual construction.

Disposed below the shell 1 concentrically thereof, is a step bearing 18 provided with a copper bronze lining, for the reception of the lower end of the vertical shaft 17, to which is keyed intermediate of its ends below the shell or retort 1 of the apparatus, a large bevel gear 10 which is operably connected to the pinion 13 of the main pulley shaft 14, 70 said shaft being properly journaled in the hanger 15 and pillow block 16. By this means the vertical shaft 17 is properly rotated and as the upper end thereof projects through the stuffing box 19 into and through the double bottom 4 of the shell 1, the upper 75 end thereof is rotated within the lower end of the jacket or shell 1.

Keyed to and rotatable upon the upper end of the shaft 17, is an agitator 11, composed of two curved arms, as clearly shown in Fig. 2, said arms having disposed thereon a plurality of projections 12 having the reduced terminals 12', so disposed that when the agitator is rotated in the direction of the arrow Fig. 2, that the said arms will properly pass through the mixture, the arm 12" upon the extreme end riding upon or near the interior surface of the jacket 1 so as to properly scrape the same and prevent the adherence thereto of any of the material to be rendered and dried. As clearly shown the terminals 12' are of lesser length than the terminals 12", but are of sufficient height to properly agitate the material within the retort or shell, and especially the portion below the upper edge of the steam jacket 2. 95

It will be noted that the outer ends of the arms of the agitator 11, terminate at a point 105 within the wall of the tank to provide a space therebetween for the passage of obstacles, such as pieces of iron, brick, etc., that may be dumped with the garbage into the reservoir. By constructing the agitator 110 as shown and with the arms 12' curved outwardly and up toward the wall of the tank,

such obstacles may be passed between the ends of the agitator and the walls of the tank without being jammed or injuring the agitator and tank. In cases where the agitator arms extend to a point very close to the wall of the tank or reservoir, such obstacles will render the device inoperative and make it necessary to remove the material from the tank or reservoir before the 10 operation of desiccation can be carried out.

From the foregoing description taken in connection with the drawings, the operation of the apparatus is readily understood, but briefly stated it is as follows: The closure 5' 15 is opened and the material to be rendered and dried or desiccated, is placed into the shell or retort 1; and steam is then introduced through the pipes 22 and 28, at four different points about the said retort or 20 shell 1.

During the operation of the boiling and final removal of the vapor from the apparatus, the material is continually agitated by the agitator disposed at the lower portion 25 and concentrically of the shell 1, and when said material has been dried or desiccated to the proper degree, the lower door 6' is opened and by the operation of the agitator, the material within the retort 1 is 30 automatically discharged through the opening 6 controlled by the door 6'.

It is evident by providing an apparatus of the design herein set forth, that animal or vegetable matter may be properly treated 35 so that the grease or oleaginous matter may be removed therefrom so that the residue

may be dried or desiccated to the proper degree to be used for various purposes, and further that by the novel construction and formation of the agitator within the lower 40 end of the jacket 1, that any pieces of metal that may be contained within the material will be moved without being wedged against the walls of the jacket to injure the same or the agitator, the peculiar angle of deflection 45 of the arms carried by the agitator preventing such obstructions from stopping the agitator or causing any injury to the apparatus.

What is claimed is:

A rendering and desiccating apparatus, having a reservoir, a shaft mounted concentrically at the bottom thereof, an agitator for the contents carried upon the upper end of the shaft and within the reservoir, the 55 ends of said agitator terminating at a point away from the wall of the reservoir to permit the passage of obstacles therebetween, a plurality of stirring arms carried by and projecting upwardly from said agitator, and one long arm connected to one end of the agitator and having its terminal curved outwardly and upwardly above the agitator to be parallel with the wall of the reservoir and in close proximity thereto.

In testimony that I claim the foregoing as my own, I have hereto affixed my signature in the presence of two witnesses.

RUDOLPH T. G. LIESINGER.
